PRESTON L. ANDREWS, OF BROOKLYN, NEW YORK

ENVELOPE FASTENER MEANS

Application filed April 8, 1929. Serial No. 353,380.

This invention relates, generally, to improvements in fasteners for envelopes; and the invention has reference, more particularly, to a self-adjusting fastener means for retaining the flaps of envelopes in closed relation to the body thereof.

This invention has for its principal object to provide a fastener means for envelope flaps of such novel construction and arrangement that the flap may be readily adjusted, closed and secured relative to enclosures of varying sizes which may be inserted within the envelope, and the flap thereupon retained in desired closed condition without risk of undue or excessive strain being exerted on either the envelope body, its flap or the fastener elements per se. To this end the novel fastener means comprises a disc-like button riveted or otherwise permanently secured to the envelope body and a longitudinally slotted fastener tab which is secured to the envelope flaps in depending projection from the free margin thereof; the slot of said fastener tab being of less width than the diameter of said button, so that the tab may be engaged under the button by passing the latter through the slot of said tab.

Other objects of this invention, not at this time more particularly enumerated, will be clearly understood from the following detailed description of the same.

An illustrative embodiment of the present invention is shown in the accompanying drawings, in which:—

Fig. 1 is a rear face view of an envelope provided with the novel fastener means made according to and embodying the principles of this invention; Fig. 2 is an edge view of the same; and Fig. 3 is a fragmentary transverse sectional view of the same, taken on line 3—3 in Figure 1 and drawn on an enlarged scale.

Figure 4 is a fragmentary detail rear-face view, showing a slightly modified button element; and Figure 5 is a sectional view through the latter, taken on line 5—5 in Figure 4.

Similar characters of reference are employed in the above described views to indicate corresponding parts.

Referring to the drawings, the reference character 5 indicates an envelope body having the usual flap 6 at its open end. This envelope body and its flap may be of any shape or size desired, and may be made of any suitable material.

Secured to the back wall of said envelope body 5, in downwardly spaced relation to the free edge of the flap 6 when said flap is folded down upon the envelope back in closed relation to the open end of the envelope body, is a disc-like button 7. This button 7 may be made of any suitable material, but is preferably made of heavy paper stock. Said button 7 is centrally secured to the envelope body 6 by means of a rivet 8, or by any other suitable means which leaves the peripheral marginal portions of the button free.

Secured to the free end of the envelope flap 6, either as an independent part or as an integral part thereof, is a downwardly projecting fastener tab 9, which is so disposed as to longitudinally align itself to the button 7 when the flap is closed over the back of the envelope body. This fastener tab 9 is provided with a longitudinally disposed elongated slot 10. If said fastener tab 9 is made integral with the flap 6 it will, of course, consist in the same material as that of which the envelope body and flap are made; when produced as an independent part, however, the same may be made of any suitable material having some flexibility.

In the use of envelopes equipped with the novel fastener means above described, after the matter desired to be enclosed in the envelope has been inserted, the envelope flap 6 is turned downwardly over and upon the back of the envelope body 5, whereupon the button 7 is passed through the slot 10 of the fastener tab 9, so as to engage the marginal portions thereof bordering the slot 10 underneath the free marginal edges of the button 7, as shown in the drawings. Owing to the elongated shape of the fastener tab slot 10, the described cooperative engagement of fastener tab and button may be easily and quickly obtained whether the flap 6 projects over the envelope back for its entire or but a part of its extent. In other words, the

novel fastener means is self-adjusting. If, for example, the matter enclosed in the envelope is somewhat longer than the depth of the envelope interior, or if the thickness of the enclosed matter tends to foreshorten the overlap of the flap 6, nevertheless the fastener tab 9 and its slot 10 will readily adjust itself to the button 7 under such conditions, and may be as readily engaged with the button so as to adequately retain the flap 6 in closed relation to the envelope body. This is indicated by the dotted lines in Figure 1 of the drawings.

Referring to Figures 4 and 5 I have shown a modified form of the button element of the fastener means, the same comprising a disc-like body so formed as to provide a depressed central portion 7' through which the rivet 8 is engaged, and an upwardly off-set peripheral flange 7'', which latter part is upwardly spaced by the depressed central portion 7' somewhat above the envelope back to which the element is secured.

With the button element thus formed and arranged the fastener tab 9 may be quickly and easily buttoned over the same, and the margins of the tab slot 10 will slide easily beneath the peripheral flange 7''.

From the foregoing it will be obvious that the novel fastener means is capable of rapid manipulation both in connection with fastening and unfastening operations; that the same provides a secure flap fastening means which lies substantially flatly upon the envelope back so as to undergo little risk of being caught or torn away when the envelope equipped therewith is mixed with quantity mail matter or otherwise; and that the same provides the advantage of readily adjusting itself to a variety of positions of the closing flap when the envelopes are used to contain enclosures of variable length or bulk.

From the standpoint of manufacturing cost, the novel fastener means is inexpensive both with respect to the materials involved and with respect to cost of production.

Having thus described my invention, I claim:

1. The combination with an envelope and its flap of a flexible fastener tab extending downwardly from the free end of said flap, the exposed portion of said tab having a single slot extending longitudinally therein, and a disc-like button riveted to the envelope body so that its peripheral portions are free, whereby said button may be passed through said flexible slotted fastener tab so that the latter may longitudinally adjust itself to said button according to the degree of overlap of said flap upon said envelope body.

2. A fastener means for an envelope having a closing flap, comprising a disc-like paper button, a rivet to permanently secure said button on the envelope back, so as

to leave its marginal portions free, and a fastener tab of more or less flexible material extending from the free end of said closing flap, said fastener tab having a single longitudinal slot through which said button may be passed with its free marginal portions overlying said tab, the fastener means thus provided permitting overlapping of the envelope flap to a greater or less degree.

3. A fastener means for an envelope having a closing flap, comprising a disc-like paper button element having a depressed central portion and a peripheral flange upwardly off-set from said central portion, a rivet extending through said central portion to secure said button element to the envelope body beneath the flap thereof, and a flexible relatively narrow fastener tab extending from the free end of said flap, said fastener tab having a single longitudinal slot through which said button element may be passed to dispose its peripheral flange in overlying relation to said tab.

In testimony that I claim the invention set forth above I have hereunto set my hand this 25 day of March, 1929.
